UNITED STATES PATENT OFFICE.

ALFRED F. HAMMERSMITH, OF CHICAGO, ILLINOIS.

EXTENSION ELECTRIC-LIGHT FIXTURE.

1,391,631.

Specification of Letters Patent. Patented Sept. 20, 1921.

Application filed August 6, 1918. Serial No. 248,573.

To all whom it may concern:

Be it known that I, ALFRED F. HAMMERSMITH, a citizen of the United States, residing at Chicago, in the county of Cook and State of Illinois, have invented certain new and useful Improvements in Extension Electric-Light Fixtures; and I do hereby declare the following to be a full, clear, and exact description of the invention, such as will enable others skilled in the art to which it appertains to make and use the same.

This invention relates to an extension electric lamp fixture.

An object is to provide a novel and efficient construction having the advantages which will appear from the following description taken in connection with accompanying drawings of one preferred embodiment.

20 In the drawings,

Figure 1 is a general side view of a fixture embodying the invention,

Fig. 2 is a detail view of the reel and connections,

25 Fig. 3 is an end view,

Fig. 4 is a longitudinal section showing the reel in elevation.

Fig. 5 is a detail end view of the casing showing the latch in the disengaged position,

30 Fig. 6 is a detail sectional view showing the yielding contact between the reel and the stationary bearing in which it is removably mounted,

Fig. 7 is a detail view of one of the binding posts, and

Fig. 8 is a transverse sectional view on the plane indicated by the line 8—8 of Fig. 4.

Within a preferably cylindrical casing 10, having the heads 11 and 12, is mounted 40 a reel 13 upon which are wound the insulated feed wires 14 which extend outward through a guide slot 15 in the wall of the casing to the lamp socket 16, the edges of the material adjacent to said guide slot preferably being rounded or beaded as shown at 17 to minimize chafing action upon the insulation.

The extremities of the feed wires are preferably connected by binding screws 18 or the equivalent thereof to terminals 19 and 20 which form elements of the reel and are separated by an insulating spacing block 21, a threaded extension 22 of one of said terminals projecting beyond the head 12 of the 50 casing being fitted with a crank 23 by which

the reel may be turned to wind the feed wire into the casing.

Secured within the casing and adjacent to the heads thereof, being separated therefrom by spacing blocks or washers 24 and 60 secured in place by screws or bolts 25, or the equivalent thereof, are hard rubber or other insulating disks 26 and 27, in the former of which is supported a bearing 28 for the reception of the rotary terminal 19, 65 while the insulating disk 27 is provided with a bearing 29 within which is mounted the hub 30 of the terminal 20. The said terminals are thus insulated from each other and from the casing while the reel which embodies said terminals is free to rotate in order to provide for the winding of the feed wires thereon.

Carried by the casing in any convenient location are the binding posts 31 and 32, 75 each of which is provided with a seat 33 for a service wire from the house system, said wire being secured in place by a binding screw 34, and a seat 35 with which cooperates a binding screw 36 for the reception of a connector 37 which extends from the binding post through a suitable opening 38 in the casing, one of said connectors extending to and being attached to the hub 30 of the terminal 20 and the other being extended 80 to and forming connection with the bearing 28, said connectors being conducted outside of the insulating disks 26 and 27 or between the planes of said disks and the heads of the cylinders or casing. 90

Secured to the reel exteriorly of the casing is a ratchet 39 of which the teeth are adapted to be engaged by a latch 40 pivotally mounted upon the adjacent head of the casing to lock the reel when the feed wire is housed or has been extended to the desired length. 95

From the foregoing description it will be seen that the feed wire may ordinarily be retained in a housed and protected position within the casing but is free upon the release of the latch to be extended as may be desired, the connection with the service system being preserved at any extension of the feed wire, and in order to insure the proper communication of the current and therefore of the contact between the terminal 19 and the bearing 28 a yielding contact element 41 may be employed as shown in detail in Fig. 6, the same being mounted in the ter- 100 105 110

5 minal 19 for sliding terminal engagement with the surface of the said bearing. It will be understood, however, that any mechanical equivalent of this arrangement may 10 be substituted to the end that regardless of the position or extent of adjustment of the reel and therefore extension of the feed wire, a perfect connection may be maintained between the service wire and the lamp socket contact.

15 The convenience of an apparatus such as described, in any of the relations suggested, will be understood, it being obvious that when not in use the feed wire may be reeled into the casing which may be secured in a convenient position upon the wall of the room or apartment, or, upon any suitable convenient object adjacent to which the light may be required. In use, the lamp 20 may hang directly from the casing at the desired extension or the lamp socket may be arranged in any suitable auxiliary support as upon a desk or writing table or may be held in the hand while examining machine- 25 ery or in giving signals or the like.

Having described the invention, I claim:—

An extension electric light fixture comprising a stationary casing, a drum within 30 said casing and composed of a central insulating member having reduced ends, and

members mounted on said reduced ends, contact members employed to connect the end members with the central insulating member and serve as binding posts, said casing having a longitudinal slot, insulated feed wires connected with said binding posts and extending through said slot to carry a lamp, a cap bearing fitted over the outer extremity of one of said end members, a threaded extension carried by the other end member of the drum and extended outwardly of the end of the casing, an operating crank mounted on the end of said threaded extension, means for locking said drum against rotation, a stationary sleeve bearing for the last mentioned end member, current conducting wires threaded into said casing and connected with the bearings for the end members of the drum, said drum including head members serving to support the bearings for the drum end members, and means for forming a yielding contact between the drum end members and the bearings therefor.

In testimony whereof I affix my signature 55 in presence of two witnesses.

ALFRED F. HAMMERSMITH.
